UNITED STATES PATENT OFFICE.

J. B. AIKEN, OF FRANKLIN, NEW HAMPSHIRE, ASSIGNOR TO J. B. AIKEN AND H. AIKEN.

KNITTING-MACHINE.

Specification of Letters Patent No. 12,933, dated May 22, 1855.

To all whom it may concern:

Be it known that I, JONAS B. AIKEN, of Franklin, in the county of Merrimack and State of New Hampshire, have invented a new and useful Attachment to Knitting-Machines, which I have denominated a "Needle-Latch Regulator," of which the following is a full, clear, and exact description, reference being had to the annexed 10 drawings, making part of this specification, in which—

Figure 1 is a view of a portion of a machine operating with a reciprocating movement, and having my improved instrument 15 attached. Fig. 2, a machine arranged for circular work. Figs. 3, 4, 5, 6 details which will be referred to hereafter.

My improvement is designed to be attached to those machines in which the barb 20 of the needle is opened and closed by a hinged or jointed latch; as heretofore constructed these latches frequently rebound and rest upon the hook or barb of the needle, which is thereby closed at a time when it 25 should be open to receive the yarn; the latter is thus prevented from entering the hook of the needle, and a loop or stitch is dropped, which causes imperfect work.

To remedy this defect is the object of my 30 present invention, which consists in passing a pointed instrument into the barb of the needle at the instant before the thread is laid in; this instrument which I call the needle latch regulation, being of such a 35 shape (as will be hereafter explained) as not only to open the latch and depress it, but to hold it open until the yarn is laid in, and the accident before alluded to is thus avoided.

40 To enable others skilled in the art to make use of my invention, I will proceed to describe the manner in which I have carried it out.

In the accompanying drawings A is the 45 "needle latch regulator." In Figs. 1 and 3 it is seen arranged for a reciprocating machine, the points a, a' , entering the barb of the needle and throwing the latch cover upon the shank; in this case the yarn carrier 50 is combined with the latch regulator, the hole c , for the passage of the yarn being made through the arm B, which carries the regulator. In such case it will be perceived

that the latch e is held down by the regulator until the yarn is laid into the hook. 55

In Fig. 4 is seen a single pointed regulator combined with the yarn carrier, and adapted to a machine for circular work, one point only being required, the motion of the regulator being continuous in one direction. As 60 in the other figures the latch e , and the yarn are represented in red, the point of the regulator just entering into the hook of the needle between the barb and the latch.

Figs. 5 and 6, are different views of the 65 regulator without the yarn carrier.

Fig. 2, represents a circular machine in which there are two sets of needles d, d' , the latches e, e , of the outer row d , being opened by the regulator A' , combined with 70 the yarn carrier B.

The regulator A^2 , which opens the barbs of the inner row of needles d' , is unaccompanied by the yarn carrier.

In all the above cases and in general, the 75 regulator is enlarged, from the point back, for the purpose as before stated not only of opening the latch, but of holding it open until the next loop is laid in. When the loop has been thrown entirely off of the 80 needle, and nothing is left within the barb to open the latch, or where the latter rebounds after having been opened, in either case the latch regulator will open the latch and prepare the hook to receive the yarn. 85

I do not confine myself to the exact form and construction herein described, but intend to make such variations therein as may be found necessary to accommodate the latch opener to the various machines to which it 90 may be found applicable.

What I claim as my invention and desire to secure by Letters Patent is—

1. The needle latch regulator constructed and operating in the manner substantially 95 as herein described for the purpose set forth.

2. I claim the needle latch regulator in combination with the yarn carrier operating substantially as herein set forth.

In testimony whereof witness my signature this fourth day of May A. D. eighteen hundred and fifty five. 100

JONAS B. AIKEN.

Witnesses:

DAVID L. ANNAN,
JOHN W. ANNAN.
